(57) **CLAIM**

The ornamental design for a drain plunger, as shown and described.

DESCRIPTION

FIG. 1 is a front side view of a drain plunger of the present invention in the extended configuration wherein the view is identical with each 180° rotation;

FIG. 2 is a side view of the drain plunger of FIG. 1 wherein the view is identical with each 180° rotation;

FIG. 3 is a top view of the drain plunger of FIG. 1;

FIG. 4 is a bottom view of a drain plunger of FIG. 1;

FIG. 5 is a perspective view of the drain plunger of FIG. 1; FIG. 6 is a front side view of the drain plunger of FIG. 1 in the compressed configuration wherein the view is identical with each 180° rotation;

FIG. 7 is a side view of the drain plunger of FIG. 6 wherein the view is identical with each 180° rotation; and,

FIG. 8 is a perspective view of the drain plunger of FIG. 6. The broken line showing in the figures is for illustrative purposes only and forms no part of the claimed design.
